UNITED STATES PATENT OFFICE.

STEPHEN KEINER, OF LOS ANGELES, CALIFORNIA.

GAMING APPLIANCE.

Application filed September 14, 1921. Serial No. 500,617.

To all whom it may concern:

Be it known that I, STEPHEN KEINER, having declared my intention of becoming a citizen of the United States, residing at Los Angeles, in the county of Los Angeles and State of California, have invented a new and useful Gaming Appliance, of which the following is a specification.

This invention relates to educational and amusement games designed principally to teach children to add, subtract, multiply and divide. To that end I provide an appliance comprising runways and pocket wheels and a number of balls either plain, colored or numbered to be released on a runway and run by gravity to a pocketed wheel arranged to spin as a hand top in which there are pockets and compartments to receive the balls. On the bottom of these compartments are letters or numerals or both that aid the players in determining what amount they have received each time the balls are released. While this gaming appliance is especially adapted to use of children it is also equally adaptable to the interest and amusement of adults.

An object of the invention is to provide a pleasing and cheap amusement device that will be exceptionally interesting, in that there is always an uncertainty as to the credits a player is to receive each time a ball is released.

Another object is to provide an appliance that is simple and cheap in construction and durable in operation.

The invention is broadly new, basic and pioneer in that it comprises upper and lower runways, an intermediate overshot pocketed wheel mounted on a horizontal axis to transfer balls from the upper to the lower runway, and a pocketed wheel arranged to spin on a vertical axis and to receive balls from the lower runway.

An object is to provide a novel game that can be played with interest by one or more players to the interest of all present.

Other objects, advantages and features of invention may appear from the accompanying drawing, the subjoined detail description and the appended claims.

The accompanying drawing illustrates the invention.

Figure 1 is a plan view of the gaming appliance with balls released thereon. The double headed arrow indicates positive rotation in either direction.

Fig. 2 is a side elevation of the appliance shown in Fig. 1.

Fig. 3 is a section on line x^3 , Fig. 1. Fig. 4 is an enlarged plan in section on line x^4 , Figs. 2 and 3.

Fig. 5 is a plan of the top with the compartments colored.

Fig. 6 is a diagrammatic view of a set of balls adapted to be used in the game.

The frame comprises a base 1, sills 2, lower runway 3, uprights 4 and cross pieces 5 thereon, that support the upper runway 6 which consists of parallel plates 7, 8, spaced apart to form between them an elongated opening 9 of less width than the diameter of the balls, and the balls 10 are adapted to travel therealong when they are released from the starting platform 11 which is slightly higher than the drop opening 12 at the lower end of the runway 6. Adjacent to the discharge opening 12 is a ball stop 13 against which the balls strike when they reach the end of the runway 6; thus causing the ball to fall through the opening 12 into the pockets 14 in the overshot wheel 15.

The upper runway 6 is preferably aslant toward the pocketed overshot wheel 15. Said wheel preferably consists of circular sides 16 spaced apart by radial vanes 17 that

are arranged equidistant apart and that are tangential to the hub 18 of the wheel. The overshot wheel is shown as having eight pockets of equal dimensions that are adapted to receive the balls 10 as they fall through the opening 12 which is so arranged that the balls 10 will fall into the tops of the pockets on that side of the wheel next to the runway so that the weight of the balls will turn the wheel on its axis and thus cause the balls to be discharged from pockets 17 onto, and be made to roll toward the front of the device along the lower runway 3 and to fall into the pockets of the top, spin top or wheel 20 which is mounted on a spindle 100

21 that has its upper end loosely mounted in a bearing 22 secured between the plates 7 and 8 and the lower end of spindle 21 is loosely mounted in a recess 23 in the plat- 5 form 1 so that it supports the top 20 above the base 1 and is mounted so that the top can be actuated by hand to spin.

In operation the spindle 21 is rotated by the hands to spin the top 20 after which any 10 or all the balls are released on platform 11 so that they pass down the runway 6 and discharge through the opening 12 into the pockets 14 where their weight causes the wheel 15 to rotate by gravity, discharging 15 the balls toward the front of the appliance so that the balls roll toward the spin top 19 and discharge promiscuously into the compartments 19; it being uncertain as to which compartments the balls enter, and it is this 20 uncertainty that makes the game so very interesting.

A number of games can be played but for the sake of brevity only one in which adding, subtracting, multiplying and dividing 25 are featured will be described.

In the bottom of the compartments 19 and near the outer wall I arrange the Roman numerals from one to eight, reading in a circle toward the right; and adjoining these 30 numerals and nearer to the center of the top are the figures one to eight arranged in reverse order to the Roman numerals or to read to the left with the Figure 1 in the compartment of the Roman numerals 8; also 35 in compartment with Roman numeral 8 and Figure 1, I place the letter A and in the other compartments reading to the right I place the letters B to H inclusive that are used to designate the compartment the players select each time the balls are released on the runway or a play is made; that is on each play the players select one or another of the compartments and tabulates the result which will be hereinafter explained.

40 The balls for this mathematical game can either be plain or colored and numbered as shown in Fig. 6; in which 1 is white, 2 is orange and 3 is brown or purple, 4 is black, 5 is yellow, 6 green, 7 blue and 8 red or pink 45 and 9 and 0 are white.

Any number of players can engage in this mathematical game and they can play for any designated total preferably a multiple of 10 say five hundred, with the player 55 reaching or passing that total first as winner. Each player is provided with a pencil and tablet to keep a record of their score.

Various rules are devised to govern the 60 various games but for the sake of brevity only those necessary to a clear understanding of the mathematical game are given.

The first rule of the game is that each 65 player is entitled to but one compartment each time the balls are released on the runway or a play is made, but that they can

select each play any compartment that they desire; and in making the selection they write the letter on their tablet that indicates their choice before the play is made after which they enter their credit when the play is made. In other words with a large number playing say thirty, ten or more or even half of the players may select the same compartment for that play; and in the next and succeeding plays diversify each making various selections; that is assuming that the ten or more players have selected compartment A and in that play the balls have entered the other compartments making A a losing place the inclination of the players 70 is to choose a winner; consequently their 75 next selection might be any one of the other compartments.

On each play or each time all of the ten balls are released on the runway the following 80 results are to be tabulated by the players.

Each player is entitled to a credit comprising the total formed by adding the amount of the figures on the balls entering 90 the compartment he or she has selected to the number in the compartment minus the Roman numeral therein; that is, assuming that a play has been made and a player has selected compartment B and that all the 95 balls except the ciphered ball has entered it. The amount from 1 to 9 inclusive on the balls is 45 with 8 in the compartment added and the Roman numeral therein subtracted 100 entitles the player to a total of 52.

At all times however the ciphered ball entering a compartment compels the players to lose one-fourth of their totals so that if it also had entered the compartment B the player would lose one-fourth of 52 or 105 have a credit of 39.

Another rule of the game is that the red ball entering any compartment alone entitles the players selecting it to multiply the amount in the compartment by 8; consequently in the play above referred to if the red ball had entered the compartment alone the player would be entitled to a credit of 72 as the Roman numeral added to 8 and multiplied by the number on the red ball 110 gives that amount.

Another rule of the game is that if the ciphered ball entering a compartment alone it cancels the total amounts that are credited to the players up to that play that have selected that compartment on that play; so that they have to start all over again. In other words if on a subsequent play the player referred to with a credit of 72 should on the next play be unfortunate enough to 120 select a compartment in which the ciphered ball enters alone he or she would lose the credit of 72 or any other amount the prior plays of the game had given them.

From the foregoing it can readily be un- 130

derstood that the game employs the mathematical features of addition, subtraction, multiplication and division in a very exhilarating and pleasing manner; that will be exceptionally beneficial to all the players as it not only increases and quickens mental activity but does so in an unlaborious way.

As previously indicated this game is especially designed for school children to give them a necessary mental exercise without tiring; and it is a game in which any number can play.

Heretofore games have been designed for even numbers of players usually a multiple of two which almost invariably leaves odd numbers of players that would like to but who cannot engage in the game for want of places. In my game either odd or even numbers of players can be engaged and in this respect the invention is broadly new, basic and pioneer.

In order to adapt the game for use of small children or kindergarten purposes the balls and compartments in the top are colored as shown in the drawing and rules of play devised that make the game exceedingly interesting and instructive to the children.

I claim.

1. A gaming appliance comprising in combination an upper ball runway adapted to deliver balls onto a wheel; a wheel mounted below the upper ball runway and adapted and arranged to receive balls delivered from said runway and also adapted to be actuated by the balls discharged from said runway; a lower ball runway adapted and arranged to receive the balls from said wheel and to deliver the same to a spinning top; and a spinning top having compartments adapted and arranged to receive the balls discharged from said lower runway.

2. A gaming appliance comprising an elevated ball starting platform, an upper ball runway adapted to receive balls from said platform and inclined downward from said platform and having a discharge opening at its lower end; a ball stop at the lower end of said runway to cause balls to enter said discharge opening; a wheel pivotally mounted below the discharge opening in said ball runway to receive balls from said runway, said wheel being adapted and arranged to be actuated by the balls falling through said discharge opening; a lower ball runway adapted and arranged to receive balls discharged from said wheel and to discharge said balls onto a spinning top; a spinning top adapted and arranged to receive balls from the end of said ball runway, said spinning top being adapted to be actuated by hand; said spinning top having compartments; and letters in said compartments for distinguishing the compartments

from each other and said compartments also having numerals that impart a numerical value to the balls entering the compartment of said spinning top.

3. A gaming appliance comprising a frame having a forward end, a ball starting platform, a ball runway supported by said frame and having one end adjacent said platform, said ball runway having an enlarged opening at its discharge end, a wheel positioned below the enlarged opening in said runway said wheel adapted to receive balls falling from said runway and to be rotated by the balls; vanes in said wheel for deflecting the balls toward the forward end of said platform as they are discharged by gravity from the pockets of said wheel, a top at the forward end of said frame, and compartments in said top, said compartments adapted to receive the balls discharged from said wheel; and said compartments having letters to distinguish them from one another and also figures and Roman numerals that impart a numerical value to balls entering any of said compartments.

4. A gaming appliance comprising a frame having a forward and rear end, a lower runway in said frame, ball starting platform at the forward end of said frame, a number of balls, an upper runway extending from said starting platform to the rear end of said frame said upper runway having a discharge opening at its rear end, a stop adjacent the discharge opening of said upper runway, a wheel below the discharged opening in said upper runway that is adapted to be rotated by said balls; vanes in said wheel that are spaced apart to form pockets, said vanes adapted to discharge the balls falling into the pockets of said wheel onto the lower runway and direct them toward the forward end of said frame, and a top at the forward end of said frame; compartments in said top that are adapted to receive said balls discharging from said lower runway, said compartments having numerals therein that impart a numerical value to balls entering therein.

5. A gaming appliance comprising a frame having a forward and rear end, a lower runway in said frame, an upper platform, an inclined ball runway extending from said upper platform to the rear end of said frame, said runway having an enlarged discharge opening at its rear end, a ball stop adjacent the discharge opening in said runway, balls for said runway said balls designated with mathematical characters, a webbed wheel below the discharge opening in said runway, vanes in said wheel that are spaced apart to form pockets of equal dimensions between the webbed sides of said wheel, said vanes adapted to deflect the balls falling into the pockets of said

wheel onto the lower runway and toward the forward end of said frame, a top at the forward end of said frame, said top adapted to spin and which also has compartments 5 that are designated by letters and provided with mathematical characters and adapted to receive the characterized balls released on said runway; the characters on the balls and compartments arranged so that a game

can be played that employs the mathematical features of addition, subtraction, multiplication and division. 10

In testimony whereof, I have hereunto set my hand at Los Angeles, California, this 3rd day of September, 1921.

STEPHEN KEINER.

Witness:

JAMES R. TOWNSEND.
